METHOD AND MEANS FOR COOLING CYLINDERS, ETC.

1,404,289.

Specification of Letters Patent. Patented Jan. 24, 1922.

Application filed August 1, 1918. Serial No. 247,736.

To all whom it may concern:

Be it known that I, WILLIAM HARPER, Jr., a citizen of the United States, and a resident of New York city, in the county of New York and State of New York, have invented certain new and useful Improvements in Methods and Means for Cooling Cylinders, etc., of which the following is a specification.

This invention relates to method and means for cooling cylinders, and has for its object to enable cylinders for compressors, combustion engines, etc., to be cooled by a fluid system wherein the circulation between heat absorbing and heat radiating portions of the system is produced by convection, each cylinder constituting an independent unit, and enabling a considerably higher working temperature to be employed than is now common. The invention will be described with particular reference to its application to rotary cylinder combustion engines, such as the Gnome type, wherein the invention is particularly advantageous because it permits a higher working temperature with consequently increased efficiency, and also because the centrifugal force due to the rapid revolution of the cylinder is availed of to accelerate the circulation. These engines are widely used at present in aviation, and it is desirable not only to increase the working temperature in order to increase the efficiency, but also to provide more uniform cooling than is now obtained with the common form of air cooling fins carried by the cylinders. Experience has shown that the leading side of a rotating cylinder having cooling fins is cooler than the opposite side, and hence the cylinder in operation gets out of round. This requires heavier cylinder construction than is necessary to withstand the pressures developed, and also requires a looser fitting piston than is necessary with a perfectly round cylinder. The result is that these engines are not now run as close to the best operating temperature as possible and are necessarily heavy.

According to this invention, a double fluid jacket is provided on each cylinder, the inner jacket being the one which receives heat through the thin cylinder wall, and the outer jacket being the heat radiating element receiving the heated cooling fluid from

the inner jacket. The flow of heated medium is from the head of the cylinder inward, thence to the outer jacket and preferably helically thereof outwardly until the now cooled fluid enters the outer end of the inner jacket. The cooled medium is heavier than the heated medium, and hence the centrifugal force due to the revolution of the cylinder causes the heated medium to flow inwardly in the inner jacket and the increasing density of the fluid in the outer jacket as it cools causes it to flow outwardly through the outer jacket as it cools and becomes heavier. Although each cylinder may be treated as a separate unit, the cylinders are herein shown as connected to a common expansible reservoir which compensates for the difference in volume of the cooling fluid at different temperatures, and also vents any gases which may be trapped in the fluid.

In the accompanying drawings—
Figure 1 is a diagram illustrating the method,

Figure 2 is a view partly in vertical section of a portion of a Gnome engine embodying the invention,

Figure 3 is a detail of a modification, and
Figure 4 shows the vent valve.

1 represents the stationary hollow crank shaft carrying the crank pin 2, master ring 3 to which are connected the master connecting rod 4 and the several jointed connected rods, 5, 5. 6 is the casing carrying engine cylinders 7, and journaled at its ends to rotate on the crank shaft 1. The fuel and lubricating oil are supplied to the interior of the crank casing 6 in the usual manner, passing through inlet valves 9 in pistons 10 to the firing space 11, the burned gases passing out through exhaust valve 12. 13 is a hood for accelerating the exhaust of the burned gases. Any desired valve actuating mechanisms can be used, as the same are not necessary for an understanding of this invention and are not illustrated herein. 14 is a hole to receive the spark plug.

The cylinders 7 are made as thin as possible, since they only have to withstand the internal pressures developed without being subject to distortion by reason of unequal cooling, and the pistons 10 are similarly constructed of light alloy and fitting in the cylinder with less clearance than is now considered essential.

Closely surrounding the cylinder so as to form the fluid space 16 is a generally cylindrical inner jacket 17, which is made of light sheet metal having high heat conducting capacity, such as aluminum, and it is rolled or scored so as to have screw threads 18 to receive the helical outer jacket 19. 20 are one or more ports connecting the lower end of the inner jacket 17 with the lower end of the outer jacket 19, the outer jacket being constructed to be screwed onto the inner jacket. The lower ends of the two jackets are clamped tight by a suitable clamping ring 21. At the upper end, the helical jacket 18 communicates with the space 22 at the upper end of the inner jacket. As shown herein, the outer jacket is clamped to the cylinder head by nut 23. There is thus provided a cylindrical fluid space close to the cylinder which is connected at each end to the helical external fluid passage, and in the case of a revolving engine the spirals are made in such a way that the centrifugal force assists in making the cool fluid ascend 25 the spiral outwardly to the head of the jacket. As the fluid is heated inside the inner jacket by contact with the thin walled cylinder, it becomes lighter and thus tends to flow inward. The helical outer jacket is 30 made of similar light and thin sheet metal having good conductivity providing a large amount of air cooling surface. Owing to the circulation outside, the fluid passes alternately from a hot to a cold side of the jacket, all the while moving helically toward the head of the cylinder, so that there is no unequal heating of the cylinder wall itself due to one side being cooler than the other on account of the movement of the cylinder 35 itself. Figure 2 shows a single outside helical passage, which will of course be proportioned according to its radiating surface and area to give the proper volume of fluid flow. In Figure 3 multiple helices 24, 25 are 40 shown, forming parallel passages, which are of somewhat greater pitch than the single helix, but it will be understood that in all cases the pitch will be proportioned according to the design of the engine as well as 45 the passage areas. More than two helices may be used where desired, as will be well understood.

It will be seen that by this method of cooling, full advantage can be taken of the 50 centrifugal force due to the movement of the cylinders, and in the case of aviation engines a heavy oil or other liquid will preferably be used as the cooling medium, because by eliminating distortion of the cylinder due 55 to unequal cooling the working temperature can be considerably raised.

26 is a ring shaped reservoir, which may be in the form of a resilient diaphragm so as to expand and contract in volume with the 60 expansion and contraction of the cooling

fluid. This reservoir is connected to each cylinder, or separately to each one as by pipes 27, 28 thereby keeping the system always full of fluid. Air or other gases in the fluid are vented through a relief valve 70 29, carrying a protecting cap 30, shown in section in Figure 4. The cooling fluid can be either water, or preferably a heavy oil having a higher working temperature than water, because the oil will increase the working temperature of the engine and hence increase the thermal efficiency, a heavy oil for aviation having the further advantage that it will not freeze at low temperatures. A pump can be used to accelerate the circulation if desired, in either a stationary or a 80 rotary cylinder engine. It will be seen that a rotary cylinder engine by reason of the helical external jacket will be evenly cooled on both sides, while the same will apply to 85 a stationary engine having a fan at one side of the cylinder according to common automobile practice. Also, greater cooling on one side than on the other of the helical jacket will accelerate the flow, especially in 90 a rotary engine. The helices will be wound in such a way that the cooling on one side will, especially in a rotary cylinder engine, accelerate the movement through the spirals, producing a whirling movement of the fluid 95 through the external jacket. It will be seen that the action of the helices is to equalize the temperature of the internal jacket even though a certain amount of direct radiation is permitted from the internal jacket, as 100 shown herein, or directly from the cylinder, since it is not essential that the interior jacket be uninterrupted circumferentially as long as it is so constructed that the flow in the interior jacket is longitudinal of the 105 cylinder. It will be understood that the terms heat absorbing and heat radiating are used herein in the relative sense, and that the functions of the jackets, as well as the flow may in many instances be reversed. It 110 will, therefore, be understood that I do not restrict the invention to the precise construction or use herein shown, as the method can be carried out by various other forms of construction and in other machines, while 115 the construction itself is not to be limited except as required by the scope of the appended claims.

What is claimed is:

1. In combination with an internal combustion engine cylinder, a jacket for maintaining a heat absorbing medium in contact therewith, a second jacket in the form of a helix surrounding first said jacket, and means for causing circulation of a heat absorbing fluid through said helical jacket to equalize circumferentially the temperature of the first said jacket.

2. In combination with an internal combustion engine cylinder, a jacket for main-

- taining a heat absorbing fluid in contact therewith and a second jacket encasing first said jacket and comprising a helical passageway communicating at its ends with the respective ends of first said jacket.
3. In combination with an internal combustion engine cylinder, a jacket for maintaining a heat absorbing fluid in contact therewith, a second jacket encasing first said jacket and comprising a helical passageway communicating at its ends with the respective ends of first said jacket and means for causing the circulation of a heat absorbing fluid through said jackets.
- 10 4. In combination with an internal combustion engine cylinder, a jacket for maintaining a heat absorbing fluid in contact therewith, and a second jacket encasing first said jacket and comprising a multiple helical passageway communicating at its ends with the respective ends of first said jacket.
- 15 5. In combination with a cylinder of an internal combustion engine of the rotating cylinder type, a jacket for maintaining a heat absorbing fluid in contact therewith, and a second jacket encasing first said jacket and comprising a helical passageway communicating at its ends with the respective ends of first said jacket.
- 20 6. In combination with a cylinder of an internal combustion engine of the rotating cylinder type, a jacket for maintaining a heat absorbing fluid in contact therewith, and a second jacket encasing first said jacket and comprising a helical passageway communicating at its ends with the respective ends of first said jacket so that centrifugal force will cause the relatively cooler fluid in the second said jacket to move outwardly and to force the relatively warmer fluid in the first said jacket to move inwardly, thus establishing circulation.
- 25 7. In combination with an internal combustion engine cylinder, a cylindrical jacket having a thread thereon, and an outer helical jacket threaded thereon.
- 30 8. The method of cooling an internal combustion engine cylinder which consists in passing a heat absorbing medium longitudinally of and in contact on all sides with said cylinder, and of returning said medium in a path external, adjacent and helical to its path while in contact with said cylinder, to permit cooling of the medium returned, and to equalize circumferentially the temperature of the medium in contact with the cylinder.
- 35 9. The method of cooling an internal combustion engine cylinder which consists in effecting a flow of fluid in contact with the cylinder to absorb heat therefrom and returning the fluid externally of the cylinder and of the path of its first said flow, and adjacent thereto, for cooling said fluid, in such manner that the flow of relatively cool fluid continuously crosses the flow of relatively hot fluid.
- 40 10. The method of cooling a cylinder of an internal combustion engine of the rotating cylinder type, which consists in effecting a flow of fluid in contact with the cylinder to absorb heat therefrom, and returning the fluid externally of the cylinder and of the path of its first said flow, and adjacent thereto, for cooling said fluid, in such manner that the flow of relatively cool fluid continuously crosses the flow of relatively hot fluid, said flow being actuated by the centrifugal force set up in the fluid by rotation of the cylinder.
- 45 11. A rotary cylinder engine comprising a casing carrying a plurality of rotary cylinders, a heat absorbing jacket and a connected heat radiating jacket on each cylinder, and an expandible fluid reservoir connected to said jackets.
- 50 12. A cooling jacket for a cylinder comprising an inner cylindrical jacket within an outer helical jacket, the latter being connected at its ends to the ends of the former, and the ends of said assembled jacket being formed to be secured on and fastened to a cylinder or the like.
- Signed at New York city, in the county of New York and State of New York.
